FREDERICK H. MIX, OF BROOKLYN, NEW YORK, ASSIGNEE TO JOSEPH DIXON CRUCIBLE COMPANY, OF JERSEY CITY, NEW JERSEY, A CORPORATION OF NEW JERSEY.

DISPLAY CASE.

Application filed June 27, 1922. Serial No. 571,233.

To all whom it may concern:

Be it known that I, FREDERICK H. Mix, a citizen of the United States, residing in Brooklyn, in the county of Kings, in the 5 State of New York, have invented certain new and useful Improvements in Display Cases, of which the following is a specification.

The invention relates to an improvement 10 in display cases adapted to contain and display packages of goods for sale.

The object of the invention is to produce an improved display case having provision for displaying the goods on sale in a more 15 pleasing and attractive manner, and having provision whereby the article sold may be readily removed from the case. Provision is also made for such advertising matter as it is desired to display in connection with 20 the goods on exhibition or on sale. The display case of the present invention is particularly adapted for displaying and exhibiting cylindrical articles, such as cylindrical wooden boxes. It has been proposed heretofore to provide display cases for exhibiting cylindrical articles, but, so far as is known, 25 no satisfactory display case for cylindrical articles, such as wooden boxes for containing leads for automatic pencils, is on the market today. These boxes as now sold are 30 commonly put up in a rectangular box. By means of the display case of the present invention these cylindrical boxes are conveniently held and exhibited so as to attract the 35 attention of customers. The invention consists in the improved display case herein-after described and particularly pointed out in the appended claims.

The preferred form of the invention is 40 illustrated in the accompanying drawings in which Fig. 1 is a front elevation of the improved display case, showing one compartment empty and the other partly filled with goods; Fig. 2 is a vertical section taken 45 through one of the compartments; Fig. 3 is a transverse section taken across the compartments; and Fig. 4 is a plan of the blank from which the compartments are formed.

50 The improved display case, as shown in the drawings, comprises a display surface or card 5 preferably of rectangular shape and which may be composed of cardboard or similar material. Mounted on the card 5 is a box 6 for containing the cylindrical ar-

ticles exhibited for sale. The card 5 is of such size that ample space is provided on one or more or on all sides of the box 6 for advertising or display matter to attract customers. The display case may be hung on 60 the wall, and for this purpose a hole 7 is provided in the top end of the card 5, or the rear side of the card 5 may be provided with an easel so as to support the display case in an inclined position on the counter 65 or show case.

The box 6 is preferably composed of cardboard or similar material and is formed so as to comprise two vertically arranged compartments 9 and 10, the upper part of which 70 is separated by a partition 11. The blank from which the box 6 is formed is shown in Fig. 4. When the blank is stamped out, the open spaces or windows 12 are cut through so as to display the articles contained in the compartments 9 and 10. The side wings 13 and 14 of the blank are first bent on the lines 15 and 16. The distance between the lines 15 and 16 determines the 75 width of the box. The wings 13 and 14 are 80 next bent under on the lines 17 and 18 to form the sides of the box, and then the end portions 19 and 20 of the wings are bent on the lines 21 and 22 and brought together to constitute the partition 11. The bottom 85 wing 23 is first bent on the line 24 to determine the length of the box and is then bent on the line 25 to form the bottom end of the box. Thus the distance between the lines 15 and 17, 16 and 18, 24 and 25 determines the 90 depth of the box and the diameter of the articles which may be contained therein. When the box has been completed by folding the blank on the dot and dash lines as 95 described above, the portions 13, 14 and 23 of the wings constitute the rear wall of the box, and this wall is secured to the card 5 by rivets 26. The transverse strips 27 which separate the upper and lower openings or windows 12 serve to strengthen the box. 100

The goods to be placed on sale or on exhibition are inserted in the compartments 9 and 10 through the upper open ends thereof. Inasmuch as the cylindrical articles are adapted to be contained in the compartments 105 in a horizontal position and to rest one on top of another, a relatively large number of articles can be contained in the compartments. The openings or windows 12 are of such size as to leave only a narrow strip 110

of material along the top and side edges of the compartments for holding the articles in place. This construction exposes a relatively large part of each article to view and facilitates the removal of the articles from the box. When the compartments 9 and 10 are full, the uppermost articles will be removed through the upper open ends of the compartments, but when a number of articles have been sold, the remaining articles may be displaced obliquely and removed through the openings or windows 12.

Having thus described the invention what I claim as new is:—

15 1. A display case comprising a card constituting a display surface, and a box containing the articles to be exhibited, said box being formed from a blank cut to provide a front portion with an opening there-
20 in to display the articles contained in the box, said blank also being cut to form integral extensions projecting from each side of said front portion, said extensions forming the side and rear walls of said box and being connected to the card, another extension provided on the blank, said last named extension being adapted to form the bottom of the box, and a partition for said box formed integral with at least one of the
25 extensions providing the rear wall.

2. A display case comprising a card having a display surface, and a box containing

the articles to be exhibited, said box being formed from a blank sheet cut to provide a front wall portion with a plurality of 35 openings therein arranged to display the articles contained in the box, said blank sheet being also provided with extensions arranged at right angles to said front wall portion, said extensions being bent to form the side and rear walls of the box and being connected to said card, another extension provided on said blank and adapted to form the bottom wall of the box, and a partition arranged between the front wall and rear wall for dividing the box into compartments which have communication with the display openings in said front wall portion, said partition being formed by an integral 40 extension of the blank.

3. A display case including a card, and a box containing the articles to be exhibited, said box being formed from a blank cut to provide a front wall portion with a series of openings therein arranged to display the 55 articles contained in the box, side and bottom wall portions formed integral with said front wall portion, a rear wall portion comprising integral extensions of the side wall portions adapted to be secured to said card 60 and having their edge portions bent to form a partition for said box.

FREDERICK H. MIX.
